UNITED STATES PATENT OFFICE.

GUSTAV B. PETSCHÉ, OF PHILADELPHIA, PENNSYLVANIA, ASSIGNOR TO SOUTHWARK FOUNDRY AND MACHINE COMPANY, OF PHILADELPHIA, PENNSYLVANIA, A CORPORATION OF PENNSYLVANIA.

VALVE-ACTUATING MECHANISM.

No. 859,331.

Specification of Letters Patent.

Patented July 9, 1907.

Application filed March 27, 1906. Serial No. 308,241.

To all whom it may concern:

Be it known that I, GUSTAV B. PETSCHÉ, a subject of the Emperor of Germany, residing in the city and county of Philadelphia, in the State of Pennsylvania, have invented a certain new and useful Improvement 5 in Valve-Actuating Mechanism, of which the following is a true and exact description, reference being had to the accompanying drawings, which form a part thereof.

- 10 My invention relates to the actuation of steam engine valves of the Corliss type and has for its object, in the first place, to secure the valve actuating spindle of such valves in position and to the valve by improved means.
- 15 Further, my object is to so construct and combine the devices directly acting upon the spindle as to avoid lateral strains and finally to generally simplify and improve the transmitting mechanism by which motion is transmitted to the valves from eccentrics or 20 other primary valve actuating devices.

The nature of my improvements will be best understood as described in connection with the drawings in which they are illustrated and in which

Figure 1 is a side elevation of a tandem compound 25 and Corliss engine provided with my improvements. Fig. 2 is a plan view of the engine. Fig. 3 a cross-section through the vacuum cylinder by which the valve is closed. Fig. 4 is a side elevation on an enlarged scale of the mechanism connected with a valve 30 spindle, the view being taken on the section line 4—4 of Fig. 5. Fig. 5 is a plan view, taken as on the section line 5—5 of Fig. 4. Fig. 6 is a longitudinal central section through one of the cylinders of the engine showing the valve system. Fig. 7 is a perspective 35 view of one of the valves. Fig. 8 a perspective view of the end of the valve actuating spindle. Fig. 9 an end view of the valve. Fig. 10 a side elevation of the hook and hook actuating mechanism. Fig. 11, a side elevation of the lever through which motion is 40 imparted to the valve spindle and Fig. 12, a perspective view of the cam device by which the hook is detached from the spindle actuating lever.

A, and A', are, respectively, the high and low pressure cylinders of the engine; B, Fig. 6, piston of the 45 high pressure cylinder; C, the piston rod; D, the connecting rod; E, the crank disk secured to the shaft F, on which is also attached the fly wheel G.

H, H', indicate the eccentrics secured on the shaft F, and by which the valve actuating mechanism is 50 operated. The eccentric H, communicates through the eccentric rod I, with the lever arm I², secured on the rock shaft I⁴, to which is also attached the lever arm I⁶, which, through the connecting rod I⁸, gives motion to the rod I¹⁰, to which rod are connected

the hook actuating levers of the low pressure cylinder. 55 The rod I¹⁰, is connected through the rod I², with the rod I¹⁴, to which are connected the hook actuating levers of the high pressure cylinder. The valves connected with the rods above mentioned are the steam admission valves of the engine cylinders. The 60 exhaust valves of the steam cylinders are actuated through a similar train of mechanism from the eccentric H', to wit, through the connecting rod I', lever I⁸, rock shaft I⁶, lever I⁷, and rods I⁹, I¹¹, I¹³, I¹⁵.

The governor mechanism indicated at J', is actuated 65 from the shaft of the engine through appropriate mechanism, such, for instance, as indicated at J, the lever actuated by the governor communicating motion through the rods indicated at J², to the hook releasing cams of the admission valves.

K, K, Fig. 6, are the admission valves controlling the flow of steam to the high pressure cylinder, K', K', the exhaust valves. These valves, and particularly the admission valves, are constructed, as shown in Figs. 7 and 9, that is to say, with cylindrical ends, indicated at 75 K², formed with transverse central slots K⁴, from the bottom of which extend bearing recesses indicated at K³. The valve spindles, indicated at L, see Figs. 4, 5 and 8, are each provided with lateral bars L', fitting in the slots K⁴, and with a plug L², which extends into and 80 is supported by the bearing K³, formed in the end of the corresponding valve. The outer ends of the valve spindles L, are supported in brackets indicated at M, M, etc., for the high pressure cylinder, and M', M', etc., for the low pressure cylinder, the brackets M extending out from the smaller high pressure cylinder so that their ends are practically level and lie in the same vertical plane with the ends of the shorter brackets M'. The ends of the brackets are provided with ball socket 85 bearings, as indicated at M², Fig. 5, and support ball 90 bearings N, with inwardly extending cylindrical ends, as indicated at N'. These ball bearings supporting the outer ends of the spindles L, as indicated, and the device by which the spindle is supported on its inner end in a bearing formed in the end of the valve and at its 95 outer end of a bracket, preferably by a ball joint, forms one feature of my invention. The spindle actuating levers O² and O³ are shown as lever arms integrally connected by a hub portion O firmly secured to the spindle L between its bearings, the hub extending out on 100 each side of the lever arms to form bearings as indicated at O', O'. The lever O² is connected to the vacuum cylinder, and the lever O³, is provided with a hook engaging latch O⁴, preferably of hardened steel.

P, P, are the bearing hubs of the hook actuating levers journaled on the hub extensions O', O', as shown, and provided with two lever arms, one, P', connecting with a link and rod system leading from the valve ac-

tuating eccentrics, while the other, P^2 , serves as a bearing for the hook shaft R , and also supports the block Q , to which is secured the spring indicated at Q' . The hook shaft R , has attached to it the hook lever R' , to which is secured the hook proper, indicated at R^2 , the shaft having also secured to it, the cam contacting lever R^3 .

S , is the hub of the hook releasing cam and is preferably journaled on the bearing N' , of the ball bearing 10 supporting the outer end of the valve spindle, the hub having formed or attached to it, the cam S' , and the lever S^2 , which lever is connected with a governor through rod system indicated at J^2 .

T , is a piston rod attached to the lever arm O^2 , and 15 to the cylinder head T' , the cylinder head having a downwardly extending central plunger T^2 , and a parallel downwardly extending outer cylinder indicated at T^3 .

T^4 , indicates a non-return escape valve of the usual 20 type by which any air in the head of the cylinder can escape therefrom, and P^3 , a restricted air admission passage by which a regulated amount of air is permitted to enter the head of the cylinder when a vacuum exists within the same.

25 U , is an annular stationary plunger secured to the frame of the engine, the plunger extension T^2 , fitting within the same and the cylinder extension T^3 , on the outside of the same.

It will be noticed that the vacuum cylinders are all 30 situated in the same vertical plane parallel with the axis of the engine cylinders, that they lie above the valve spindles and in the same plane with the actuating link system leading from the eccentric and by which the hooked levers of the admission valves are 35 operated.

It is I believe new with me to have the actuating rods for the hook levers and the vacuum cylinders lie in the same plane with each other and with the spindle actuating levers O^2 and O^3 , and it is also I believe new 40 with me in a tandem compound engine to so combine the admission valve actuating mechanism that all the spindle actuating levers and the parts connecting thereto lie in the same vertical plane. The advantages of this construction in avoiding lateral strains and in 45 simplifying tandem compound engines are obvious.

My leading idea, that of avoiding lateral strains in the valve actuating mechanism of valves of this general type is further embodied in the construction by which the hook actuating levers have their bearings on the 50 heads O' , O' , of the spindle actuating levers, the lever arms P^2 , P^2 , carrying the hook pivoted between them and lying in the same plane with the lever arm O^3 upon which the hook acts and the general preservation of correct alinement is further promoted by giving the 55 cam head S a bearing on the ball bearing extension N' , which, in the construction shown, must always preserve correct alinement with the spindle and the parts secured to the spindle.

There is of course nothing essentially new in the 60 general character of the valve mechanism, the operation of which is familiar to all engineers, and a very brief description, if any, is necessary in connection therewith; I will note however that the normal position of the valves is closed with the cylinder and plunger of the vacuum cylinder in the position shown in

Fig. 3. The oscillation of the hook actuating lever brings the hook R^4 , into engagement with hook engaging ledge O^4 , turning the valve spindle toward the left as shown in Figs. 4 and 5 and forcing the vacuum cylinder and its attached plunger upward, a small amount of air being permitted to enter the head of the cylinder through the restricted passage T^6 , at some time during the downward movement of the stroke, the cam S' coming in contact with the lever arm R^3 , pushes the hook out so as to disengage it from the arm O^3 , whereupon the vacuum in the vacuum cylinder at once causes the return of this cylinder to normal position as shown in Fig. 3, and the closing of the valve, the small amount of air which has entered the vacuum cylinder serving as a cushion on its downward stroke, 70 but escaping through the non-return valve T^4 .

Having now described my invention, what I claim as new and desire to secure by Letters Patent is

1. In an engine, a valve of the Corliss type having, at one end, means for connecting it to an actuating spindle 85 and a bearing for the end of said spindle in combination with a bracket, a self adjusting bearing for the outer end of the spindle, supported on said bracket, a spindle supported in the bearing of the valve and the self adjusting bearing and valve actuating mechanism connected to said 90 spindle.

2. In an engine having valves of the Corliss type a valve spindle, actuating levers secured to said spindle through a hub having bearings formed thereon on both sides of the levers and catch actuating levers journaled on 95 the hub bearings.

3. In an engine, a valve of the Corliss type having, at one end, means for connecting it to an actuating spindle and a bearing for the end of said spindle in combination with a bracket, a self adjusting bearing for the outer end 100 of the spindle supported on said bracket, a spindle supported in the bearing of the valve and the self adjusting bearing valve, actuating levers secured to the spindle between its bearings through a hub having bearings on both sides of said levers and catch actuating levers journaled 105 on said hub bearing.

4. In an engine, a valve of the Corliss type having, at one end, means for connecting it to an actuating spindle and a bearing for the end of said spindle in combination with a bracket, a self adjusting bearing for the outer end 110 of the spindle supported on said bracket, a spindle supported in the bearing of the valve and the self adjusting bearing valve, actuating levers secured to the spindle between its bearings through a hub having bearings on both sides of said levers, catch actuating levers journaled on 115 said hub bearing and a catch releasing cam journaled on a bearing formed on the inner end of the self adjusting spindle bearing.

5. In an engine of the Corliss type a valve actuating spindle in combination with actuating levers secured 120 thereto, catch actuating levers journaled on each side of the spindle actuating levers a connecting rod attached to the catch actuating levers and lying at one side of and in the same plane as the spindle levers and resilient valve closing mechanism connected to the spindle levers and 125 lying in the same plane as the spindle on the side opposite to that of the connecting rod.

6. In a compound tandem engine of the Corliss type a series of admission valve spindles for both cylinders having actuating levers secured thereto in a common plane, 130 in combination with catch actuating levers for each spindle, a line of connecting rods or links lying below and in the same plane as the spindle levers and connected to actuate the catch levers and a series of resilient spindle actuating devices situated above and in the same plane as 135 the spindle levers.
